UNITED STATES PATENT OFFICE

2,398,872

CELL CASE PARTITION MACHINE

Otto Ullsmith, Chicago, Ill., assignor to Traver Corporation, Chicago, Ill.

Application February 2, 1945, Serial No. 575,895

11 Claims. (Cl. 93—37)

This invention relates to cell case partition machines, and has for its principal object a new and improved machine of this type.

It is a main object of the invention to provide a new and improved roller box for feeding the strips or ribbons of material from which the cell case partitions are made.

Another object of the invention is to provide a roller box that is easy to adjust to vary the spacing between adjacent ribbons thereby to make cell case partitions of various sizes.

Still another object of the invention is to provide a roller box that is of simple construction and is adapted to fit into existing cell case partition machines.

Still another object of the invention is to provide a roller box that is inexpensive to construct, inexpensive to adjust and inexpensive to maintain.

Further objects of the invention not specifically mentioned here will be apparent from the detailed description and claims which follow, reference being had to the accompanying drawing in which a preferred embodiment of the invention is shown by way of example and in which:

Figure 1 is a plan view of the improved roller box;

Figure 2 is an elevational view partly in section taken substantially along a line 2—2 of Figure 1 looking in the direction of the arrows;

Figure 3 is a cross sectional view taken substantially along the line 3—3 of Figure 1 looking in the direction of the arrows.

Cell case partitions such as are commonly used in cartons or boxes to form pockets into which fragile articles such as eggs, cookies, glassware, etc., may be placed, are now put to such a variety of uses that many variations of the spacing between adjacent members of the partition are necessary. Machines for making these partitions must necessarily be adjustable so that a large variety of different partitions can be made on the machine and the machine must be capable of being readily changed from one partition size to another. In the Patent 1,710,467, issued to Beck April 23, 1929, there is shown an adjustable cell case partition machine capable of fulfilling these requirements.

In the making of partitions a roll of fibre stock of suitable thickness is fed into the machine, punched at spaced intervals, and slit into ribbons which are turned out of the plane of the sheet and fed forwardly to a point of assembly to form one set of members on the partition.

A second web of material is fed into the machine, punched and cut into strips, which are disposed at right angles to the ribbons and intermeshed therewith to form the partition.

The mechanism by which the ribbons of stock are fed forwardly to the assembly position is known as a roller box and consists of a box-like frame containing a plurality of upstanding rollers which are geared together and rotated at such a speed as to feed the ribbons forwardly the required distance during interval of time between sequential operations of the transverse strips. The present invention relates specifically to the so-called roller box mechanism of the machine.

15 In the above mentioned Beck patent the roller box carries a main drive shaft which extends transversely of the ribbons and through which the rollers are driven by suitable miter gears. In a box of this type the minimum distance between adjacent ribbons is determined by the diameter of the gears on the roller shaft and in certain instances it has been desirable to make cell cases with adjacent ribbons closer together than the Beck machine has been capable of making. Furthermore, in order to prevent excessive wear of the relatively high speed roller gears it has been necessary to encase these gears in grease. In adjusting the Beck roller box from one roller spacing to another it has been necessary to remove the box from the machine, open it up, make the adjustments required and then repack the box with grease and re-install it in the machine. As a result, change-over from one cell case size to another has been an expensive and somewhat messy job.

35 The roller box of the present invention does away with the rollers upstanding alongside of the ribbons and substitutes disks which are carried on a main drive shaft and are provided with set screws through which the disks are anchored in spaced apart relation therewith. The ribbons are held against the disk by small rollers that are supported on pivoted arms and are pressed against the ribbons by suitable means such as springs. The operating mechanisms of the roller box of the present invention are all out in the open and adjustment can be accomplished without disturbing the lubricating system of the main shaft. Since the disks are relatively thin a much closer spacing of the ribbons can be achieved than has been possible heretofore, and this adjustment can be changed without removing roller box from the machine.

Referring now to the drawing in more detail—
55 the roller box of the present invention, shown by

way of example, consists of a generally rectangular box-like frame 1 which is provided with laterally projecting feet 2, that are perforated at 3 to permit mounting the box upon the supports of existing machines. Extending between and journaled in the end members 4 of the frame is a main shaft 5 upon which is mounted a plurality of friction disks 6 each of which is provided with a hub 7 through which a set screw 8 is threaded to permit keying the disk to the shaft 5. Shaft 5 may be supported in suitable low friction bearings such as roller bearings or ball bearings if desired. Shaft 5 extends beyond one end plate 4 and is equipped with a suitable driving means shown as a grooved pulley 9, by which the shaft is rotated by power furnished either from the main shaft of the machine or through a separate variable speed motor as desired.

A mounting rod 10 extends between the end plates 4 of the frame and is spaced from and substantially parallel to the main shaft 5. Slideably mounted upon this rod 10 are a plurality of blocks 11 which are threaded to receive a stud screw 12, the shaft of which forms a pivot for supporting an arm 13. The free end of the arm terminates adjacent the disks 6 and carries a small roller 14 which may conveniently be a self-contained ball bearing assembly. The length of the arm 13 is such that the roller 14 engages the disk 6 along a line disposed in a vertical plane through the axis of the shaft 5, when the box is disposed with the shaft horizontal as shown.

Mounted between the end plates 4 is a second mounting rod 15 upon which is located a plurality of blocks 16, each of which contains a stud screw 17 by which the block is clamped in position on the rod. Each block 16 carries a leaf spring 18 which extends upwardly and engages the arm 13 and is tensioned to press the roller against the disk with sufficient force to pull the ribbons of material as the disk is rotated.

Side member 19 of the frame terminates below the lower edge of the rollers 14 and serves as a support for the lower edge of ribbons 20. The opposite side 21 of the frame is somewhat thicker than the side 19 and contains a groove 22 which serves as a mounting groove for shears 23, which operate to sever the ribbons in the manner fully described in the above mentioned Beck patent. Side member 21 terminates in the same horizontal plane as side 19 and serves also as a support for the bottom edges of the ribbons. Shears 23 carry guide blocks 24 which overlie the top edge of the side 21 and serve to guide the ribbons through the shears.

End plates 4 of the frame carry upwardly extending rods 25 which project through a hold down bar 26 that is locked on the rod by suitable means such as set screws and is in engagement with the top edges of the ribbon so as to prevent these ribbons from crawling up away from the rollers.

In setting the machine set screws 8 are loosened and the disks 6 spaced along the shaft 5 in correct relation to get the desired spacing of the ribbons 20. Stud screws 12 are loosened and blocks 11 moved along the mounting block 10 to position the arms and roller 14 alongside the disks, the stud screws then being tightened to maintain this adjustment. Set screws 17 are loosened and block 16 moved along the rod 15 to cause leaf springs 18 to place the desired tension upon the arms. This completes the adjustment and the machine is ready for operation.

Shaft 5 is rotated clockwise as seen in Figure 3,

thereby to rotate the disks. The frictional engagement of the ribbons to the disk along the line of pressure of the roller 14 urges the ribbons to the right, Figure 3. Intermittently the ribbons are held stationary by the main feed rollers of the machine in the manner best explained in the above mentioned Beck patent, and the disks slip on the ribbons. When the feed rolls are released to advance the ribbons they are pulled along by the movement of the disks 6, and pushed past the shears and into the assembly position generally indicated at 30, Figure 3.

The roller box of the present invention is possessed of many advantages. It can be economically built as a sturdy, self-contained unit, capable of being inserted in the existing mountings of a machine. It can be readily adjusted to any desired spacing of ribbons and the ribbons can be spaced much more closely together than has been possible heretofore. Adequate lubrication of the main rotating parts of the box can be more readily achieved, since this lubrication is not disturbed during adjustment of the box. All rotating parts may be provided with low friction bearings, and low maintenance thereby assured.

While I have chosen to illustrate my invention by showing and describing a preferred embodiment, I have done so by way of example only, as there are many modifications and adaptations which can be made by one skilled in the art within the teachings of the invention.

Having thus complied with the statutes and shown and described a preferred embodiment of my invention, what I consider new and desire to have protected by Letters Patent, is pointed out in the appended claims.

What is claimed is:

1. In a roller box for cell case partition machines, a rotatable shaft, a plurality of disks on said shaft, means including a set screw for each disk for fixing the disk on the shaft to be rotated thereby, a roller for each disk, a supporting arm for each roller, means pivotally supporting said arms each in juxtaposition to one of said disks, and means acting on the arm to force the roller carried thereby against the disk under tension.

2. In a roller box for cell case partition machines, a rotatable shaft, a plurality of disks on said shaft, means including a set screw for each disk for fixing the disk on the shaft to be rotated thereby, a roller for each disk, a supporting arm for each roller, means pivotally supporting said arms, each in juxtaposition to one of said disks, spring means engaging the arm and tensioned to force the roller against the disk, a bar, and means for holding said bar substantially parallel to said shaft and over said rollers and disks.

3. A roller box for cell case partition machines comprising, a frame adapted for mounting in the machine, a shaft journaled in said frame, a plurality of traction disks fixed on said shaft and adapted to be rotated thereby, an arm for each disk, means pivotally supporting said arms on said frame, roller means carried by each arm and adapted to engage the disk, and means for holding said roller means in firm engagement with the disk.

4. A roller box for cell case partition machines comprising, a frame adapted for mounting in the machine, a shaft journaled in said frame, a plurality of traction disks fixed on said shaft and adapted to be rotated thereby, an arm for each disk, means pivotally supporting said arms on

said frame, roller means carried by each arm and adapted to engage the disk and spring means engaging each arm and the frame and tensioned to hold said roller means in firm engagement with the disk.

5. A roller box for cell case partition machines comprising, a rectangular frame, end members included in said frame, a shaft journaled in said end members and extending therebetween, a plurality of disks adjustably fixed on said shaft between said end members and extending above the top edges thereof, side members on said frame terminating in a plane through the top edges of said end members and adapted to support strips of partition material extending across said frame and disposed each against a face of one of said disks, a roller for each disk, means supporting said roller in contact with the strip along a line disposed at right angles to the edge of said strip that engages said side members, and means for maintaining said rollers in contact with said strips under tension to cause rotation of the disks to move said strips across said frame.

6. A roller box for cell case partition machines comprising, a rectangular frame, end members included in said frame, a shaft journaled in said end members and extending therebetween, a plurality of disks adjustably fixed on said shaft between said end members and extending above the top edges thereof, side members on said frame terminating in a plane through the top edges of said end members and adapted to support strips of partition material extending across said frame and disposed each against face of one of said disks, a roller for each disk, means supporting said roller in contact with the strip along a line disposed at right angles to the edge of said strip that engages said side members, means for maintaining said rollers in contact with said strips under tension to cause rotation of the disks to move said strips across said frame, a hold down bar extending from end to end of said frame and means on said end members for holding said bar to prevent said strips from rising off of said side members during said movement.

7. A roller box for cell case partition machines comprising, a frame adapted to be removably mounted in the machines, a shaft journaled in said frame, a plurality of traction disks fixed on said shaft and adapted to be rotated thereby, a mounting rod fixed in said frame, a plurality of arms corresponding in number to the number of said disks, means pivotally mounting said arms on said mounting rod for swinging around axes parallel to the faces of said disks, roller means mounted on each of said arms adapted to engage

the corresponding disk, and spring means for forcing said roller means into firm engagement with said disks.

8. A roller box for cell case partition machines comprising, a box-like frame, a main shaft journaled in the end members of said frame and extending therebetween, a plurality of disks adjustably fixed in spaced apart relation along said shaft, a mounting rod extending between and fixed to said end members, roller arms adjustably fixed on said mounting rod in spaced apart relation, said arms being pivoted with respect to said rod, rollers carried on said arms and engaging said disks, a second mounting rod spaced from said shaft and first rod and extending between and fixed to said end members, and a plurality of leaf springs adjustably fixed on said second mounting rod in spaced apart relation with each spring engaging one of said roller arms to press the roller carried thereby against a disk.

9. A roller box for cell case partition machines comprising, a frame adapted for mounting in the machine, end plates in said frame, a shaft extending between said end plates, journals in said plates supporting said shaft, a plurality of disks fixed upon said shaft and adapted to be rotated thereby, means for pressing a strip of material against the disk to cause a rotation of the disks to move the strips, a mounting plate on said frame and extending between said end plates, and shear means mounted on said mounting plate and adapted to sever said strips of material.

10. In a roller box for cell case partition machines, a rotatable shaft, a disk fixed upon said shaft, work supporting members disposed in a common plane and on opposite sides of said shaft and disk and at right angles to the face of said disk, a roller, means supporting said roller in engagement with said disk along a line disposed at right angles to said common plane, and means for maintaining said roller in engagement with said disk under tension.

11. In a roller box for cell case partition machine, a rotatable shaft, a disk fixed upon said shaft, work supporting members disposed in a common plane and on opposite sides of said shaft and disk and at right angles to the face of said disk, a roller, means supporting said roller in engagement with said disk along a line disposed at right angles to said common plane, means for maintaining said roller in engagement with said disk under tension, and means parallel to and spaced from said common plane for holding work against said work supporting members.

OTTO ULLSMITH.
